CLAIM

The ornamental design for an ear dryer, as shown and described.

DESCRIPTION

FIG. 1 is a perspective view of an ear dryer showing our new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged view of the bounded area 8 of FIG. 1; and,

FIG. 9 is an enlarged view of the bounded area 9 of FIG. 1. The dash-dot-dash lines shown in the figures depict the border of enlarged areas and form no part of the claimed design. The evenly spaced broken lines shown in the figures depict portions of the ear dryer that do not form part of the claimed design.
